UNITED STATES PATENT OFFICE.

JOHN H. KELLOGG, OF BATTLECREEK, MICHIGAN.

DESIGN FOR A CHAIR.

SPECIFICATION forming part of Design No. 36,771, dated February 2, 1904.

Application filed January 11, 1904. Serial No. 188,667. Term of patent 14 years.

To all whom it may concern:

Be it known that I, JOHN HARVEY KELLOGG, a citizen of the United States, residing at the city of Battlecreek, in the county of Calhoun 5 and State of Michigan, have invented a new, original, and ornamental Design for a Chair.

My new, original, and ornamental design for a chair is clearly illustrated in the accompanying perspective drawing.

10 What I claim as new, and desire to secure by Letters Patent, is—

The ornamental design for a chair, substantially as shown.

In witness whereof I have hereunto set my hand in the presence of two witnesses.

JOHN H. KELLOGG.
